UNITED STATES PATENT OFFICE.

CHRISTIAN F. THEODOR STEINWAY, OF NEW YORK, N. Y.

PIANO-ACTION.

SPECIFICATION forming part of Letters Patent No. 270,914, dated January 23, 1883.

Application filed July 15, 1882. (No model.)

To all whom it may concern:

Be it known that I, CHRISTIAN F. THEODOR STEINWAY, of New York, N. Y., have invented a certain Improvement in Piano-Forte Actions, of which the following is a specification.

My improvement relates to that class of piano-forte actions in which the movable trains of levers and links for actuating the hammers 10 respectively are operated by being pushed upward.

It is the object of my invention to diminish the weight borne upon the inner ends of the keys when such actions are at rest. I accomplish this by carrying a portion of such weight upon expanding springs which derive their support from the action-frame. The springs which I employ for this purpose are of a peculiar shape, which especially adapts 20 them for adjustment to the desired object. By thus relieving the keys from a portion of the weight of the action I am enabled to dispense with one or more of the counterpoise-weights heretofore introduced into the forward parts of the keys. Therefore a lighter 25 touch suffices to depress the key, and the action, as a whole, is increased in sensitiveness and delicacy.

The accompanying drawing, which illustrates my improvement applied to a piano-forte action substantially like that shown and described in Reissued Letters Patent No. 9,013, dated December 30, 1879, granted to me for an improvement in piano-forte actions, is a 35 vertical section of a piano-forte action-frame, showing in elevation one of the keys and one of the trains of levers and links by which motion is transmitted from the key to the hammer; also showing in side elevation my spring 40 for relieving the key from a portion of the weight of the action.

The drawing exhibits a section of the keyboard bed A, to which is secured the usual balance-rail, B, provided with the balance-pin 45 a, which forms the guide for the key C. The key is provided with the pilot-screw c, the rounded head of which bears upon the cushioned under surface of the shoulder c', projecting downward from the under side of the intermediate or balance lever, d. The lever d

carries the jack e, by means of which motion is transmitted to the hammer-arm H.

The drawing also represents the action-frame, consisting of the metallic standards D, to which are fastened the tubular metallic 55 rails E. The usual provision is made for fastening the standards at the bottom, and for adjusting the various parts of the action. When the parts are at rest a portion only of the weight of the action is borne upon the 60 head of the pilot-screw c. The remaining portion is borne, through the medium of the relief-spring N, upon the cushioned bar O, affixed to the rail E of the action-frame. The relief-spring is a wire coiled to form the eye 65 n for the reception of the pin P, inserted transversely through the side walls of the groove p, formed in the side of the shoulder c'. The ends of the coil are prolonged to form respectively the upper arm, n', and the lower arm, n'', 70 of the relief-spring. The upper arm, n', is sinuously curved in a vertical plane, as shown, and its free end bears upon the bottom of the groove p', formed in the under side of the balance or intermediate lever, d. The lower arm, 75 n'', is bent in a long curve, presenting its convex side downward. Its free end is formed into the hook Q to receive the bolster or link q, affixed to the intermediate lever, d. When the parts are at rest, the arm n'' bears upon the 80 cushioned surface O' of the bar O, which is secured to the action-frame rail E by a suitable number of screws, one of which, O'', is shown in the drawing. As the forward end, C', of the key is depressed, and the intermediate lever and its connections pushed upward, the lower arm, n'', rolls over the curved surface of the cushion O' without slipping thereon, and is finally caught and held by the bolster q. 85

By varying the curvature of the arms, especially the curvature of the upper arm, n', the effective lifting force of the relief-spring may be adjusted with the greatest nicety.

By the use of my relief-spring one or more 95 of the usual counterpoise-weights, like the weight R, inserted into the forward part, C', of the key C, may be dispensed with, thus diminishing the static inertia of the mass required to be moved in operating the action. 90

I claim as my invention in a piano-forte action substantially such as described—

1. The intermediate or balance lever, *d*, and the relief-spring *N*, in combination with the cushioned bar *O*, as and for the purpose set forth.

2. The lower arm, *n²*, of the relief-spring *N*, curved as shown, in combination with the curved surface of the cushion *O'*.

3. The relief-spring *N*, carried by the intermediate lever, *d*, in combination with the bolster *q*, substantially as described.

C. F. THEODOR STEINWAY.
